UNITED STATES PATENT OFFICE.

ALBERT D. GROVER, OF NEW YORK, N. Y., ASSIGNOR TO AUTOSALES CORPORATION, A CORPORATION OF NEW YORK.

COIN-CONTROLLED MECHANISM FOR VENDING MACHINES.

Application filed September 26, 1918. Serial No. 255,763.

To all whom it may concern:

Be it known that I, ALBERT D. GROVER, a citizen of the United States, and a resident of New York, in the county of New York and State of New York, have invented certain new and useful Improvements in Coin-Controlled Mechanism for Vending Machines, of which the following is a specification.

10 My invention relates to improvements in coin-controlled mechanisms adapted for use in vending machines, although it is capable of use in coin-controlled machines of any kind. The particular object of my invention is to provide a coin-controlled mechanism which will operate only with a predetermined plurality of coins. In other words, assuming my invention to be applied to a vending machine, the purchaser is required to deposit two or more coins before the machine will deliver a piece of goods. The simplicity of my invention enables it to be applied to existing machines which have heretofore delivered a piece of goods 20 for one coin (say, one cent), and which may be readily modified, without any extensive changes, to sell a piece of goods for two or more cents. This is particularly desirable at the present time, when the cost of 25 goods and labor has so far advanced within the last few years that vending machines which heretofore could be operated at a reasonable profit upon a one-cent basis, can no longer produce any profit by selling 30 goods at the old price of one cent. These old "penny" slot machines, as they are usually called, may be readily converted into two-cent or three-cent machines by the application of my invention. Furthermore, 35 my invention is of such a character that a two or three-cent machine may as readily be converted into a penny machine, if desired.

In the broad aspect of my invention, as defined in the appended claims, the basic features may be mechanically carried out in many different ways, and the specific mechanism shown in the accompanying drawings is merely for the sake of illustration. In 45 these drawings,

Fig. 1 shows a plan view of a coin-con-

trolled mechanism embodying my invention;

Fig. 2 is a longitudinal cross-section on line 2—2 of Fig. 1, the operative parts being shown in normal position;

Fig. 3 is a transverse cross-section approximately on line 3—3 of Fig. 2;

Fig. 4 is an inverted plan view of the mechanism, the operative parts being shown in normal position;

Fig. 5 is a view similar to Fig. 2 (with parts broken away), showing how the coin-carrier is released for operative movement through the medium of two coins deposited in the coin-carrier;

Fig. 6 is a view similar to Fig. 5, showing how a single coin fails to operate the machine;

Fig. 7 is a transverse cross-section, enlarged for the sake of clearness, approximately on line 7—7 of Fig. 2, looking in the direction of the arrows; this figure shows a preferred way of mounting a coin-carrier requiring two coins; and

Fig. 8 is a view similar to Fig. 7, showing how the coin-carrier may be readily changed to operate with three coins.

I have not deemed it necessary to illustrate an entire vending machine, but only so much of the mechanism thereof as will be found helpful in understanding the operation of my invention. It will be understood that the parts are mounted in a closed casing, of which I have shown only the plate A which may be considered as part of the outside front wall of the casing. The plate A is shown in a form in which it has actually been used. Broadly speaking, the plate A may be referred to as a suitable support.

To the rear part of plate A are secured the rearwardly extending arms 1 and 2 on which is supported the goods magazine indicated as a whole by M. This magazine may be of any suitable construction. The stack of vendible articles in the magazine is indicated by V in Fig. 2. Between the arms 1 and 2 is slidably mounted a block B, which for convenience I will call the ejector block. The block B is provided with lateral extensions 3 arranged to engage in

slots 4 in the arms 1 and 2, whereby the 95
100

block is guided in its reciprocating movements. At its upper end the ejector block has connected therewith the ejector E which is shown in the form of a rearward extension in line with the lower-most package of goods in the magazine. Of course, it will be understood that the ejector may be of any suitable form or construction, and may be mounted in any convenient way. For the sake of simplicity, I have shown the ejector E merely in the form of an arm projecting rearwardly from the block B. A plunger P is suitably connected to the ejector block for operating the ejector by hand from the outside of the machine. A coil spring 5, pressing at its front end against the hollow plunger P, returns the plunger and the connected parts to normal position as soon as the plunger is released. The steady-ing rod 6 for the spring 5 may conveniently be secured to the cross-bar 7 that connects the arms 1 and 2. It will be seen from the foregoing that when the plunger is pushed in (assuming that it is free to operate), the ejector E will push the bottom piece of goods out of the magazine, whence it falls into a position for removal by the purchaser, as will be well understood. The operation of the ejector E is under the control of the coin-mechanism which I will now describe.

To the plate A is secured the plate 8, which is spaced from the plate A by means of packing members 9, as best shown in Figs. 7 and 8. These packing members are in the form of metal strips provided with holes through which pass the screws or other fastening members 10. The upper plate A, the lower plate 8 and the side members 9 form a chamber or recess R in which operates the coin-carrier indicated as a whole by C. The depth of the chamber R is regulated by the number of packing strips 9 employed. In Fig. 7 there is one packing strip on each side, and in Fig. 8 there are two packing strips 9 on each side. The depth of the chamber R will depend upon the thickness of the coin-carrier, and the thickness of the coin-carrier will depend upon the number of coins with which the machine is to operate. The coin-carrier C adapted to operate in the chamber R consists of two plates or sections 11 and 12 which are rigidly connected together by any suitable means and fastened at the rear end to the block B by means of screws 13, or otherwise. An angular bracket plate 14 is preferably interposed between the coin-carrier and the heads of the screws 13, so as to secure a firmer attachment. The coin-carrier C is thus rigidly connected with the hand-operable plunger P. When therefore, the plunger P is pushed in, the coin-carrier C and the ejector E operate as a single member. This particular construction is, of course, not essential, and in the broader

aspect of my invention there may be any suitable operative connections between the hand-operable member P, the ejecting member E, and the coin-carrier C.

The coin-carrier C is provided with a coin-receiving opening 15 which is formed by means of two corresponding openings in the sections 11 and 12. The coin-opening 15 is normally in alignment with the coin-entrance slot 16 in the top plate A. Any suitable mechanism may be associated with the coin-carrier C to be acted upon by the deposited coins. In the present instance, I have shown, by way of illustration, a coin-actuated device similar to the one set forth in the Romans and Grover Patent No. 625,123, dated May 16, 1899. This device comprises a dog or pawl 17 pivoted at 18 to the ears or studs 19 depending from the plate 8, as best shown in Fig. 4. A coil spring 20 mounted on the shaft 18 normally presses the free end 21 of the dog 17 upwardly into the path of movement of the lateral lug 22 on the coin-carrier C. The lug 22 is indicated in dotted lines in Fig. 1 and in full lines in Fig. 4. As long as the hook end 21 of the dog 17 remains in the path of movement of the lug 22, it is clear that the inward movement of the coin-carrier or coin-slide C, will be arrested the moment the lug 22 encounters the hook end 21. This preliminary movement of the coin-carrier is insufficient to cause the ejection of the lowermost package by the ejector E.

In order to secure a full operative movement of the coin-carrier C and the ejector E, it is necessary that the hook end 21 of the dog 17 be moved out of the path of the lug 22. This unlocking of the coin-carrier is in the present instance accomplished by means of the arm or segment 23 rotatably mounted on the shaft 24. The segment 23 is rigidly connected with the sleeve 25 which is rotatable on the shaft 24. One end of the shaft 24 is mounted in the bracket 26 projecting downwardly from the plate 8, and the other end of the shaft 24 is in the form of a flat extension 27 engaging in the slot 28 of the projection 29 formed on the plate 8. This is best shown in the inverted plan view of Fig. 4. By reason of this mounting, the shaft 24 is not rotatable, but the end 27 thereof is movable up and down in the slot 28, for a purpose which will be presently explained. The sleeve 25 carries a small gear or pinion 30, the teeth of which are arranged to mesh with the teeth 31 of the coin-carrier C, as best indicated in Fig. 4. Because of this connection between the coin-carrier and the coin-testing segment 23, it will be clear that whenever the coin-carrier moves, the segment 23 is rotated.

The action of the deposited coins on the segment 23 to move the dog 17 into releasing position, is as follows: The segment 23, as

seen from Fig. 4, is arranged substantially along the diameter of the coin-opening 15, so as to engage the coins along a central line. With the parts in their normal position, as shown in Fig. 2, when two coins have been deposited in the coin-opening 15 of the coin-carrier C and when the plunger is pushed in, the coin-segment 23 will be rocked upwardly from the position shown in Fig. 2 to the position shown in Fig. 5. In this figure, the two deposited coins are indicated at D and D'. As the coin-carrier moves forwardly with the two coins, the pointed end a of the segment 23 comes into contact with the underside of the bottom coin D', and the shaft 24 is thus forced downwardly at the end which carries the pin 27. As the shaft 24 lies immediately over the coin-dog 17, this downward movement of the shaft rocks the dog 17 downwardly and moves the hook end 21 out of the path of the lug 22. Consequently, the coin-carrier becomes unlocked and is, therefore, free to be moved forwardly to the full extent, whereby the ejector E pushes the bottom piece of goods out of the magazine. The deposited coins drop out of the coin-carrier after they have passed the coin-testing segment 23, and fall into a money receptacle suitably arranged within the machine.

The dog 17 is guided in its up and down movements by means of a pair of guide posts 32 and 33 depending from the plate 8.

Let us now suppose that it is attempted to operate the machine by means of less than the prescribed number of coins. In this particular instance, that would mean a single coin. When only one coin is deposited and the plunger P pushed in, the segment 23, instead of being forced downwardly as in the presence of the required number of coins, encounters no resistance and lifts the forward end of the coin upwardly, as indicated at D², in Fig. 6. As a result, the dog 17 is not moved out of locking position and the coin-carrier remains locked against further inward movement. The preliminary inward movement of the coin-carrier from its normal position to the position shown in Fig. 6, is not sufficient to cause ejection of the goods. This preliminary movement is allowed for the purpose of testing the deposited coin or coins. When the plunger P is released after it has been attempted to operate the machine with a single coin, the coin-carrier is moved back to its original position, carrying with it the coin D². The latter may then be removed by the intending purchaser. This removal is rendered easy by reason of the cutout portion 34 at the front edge of the plate 8. This allows a pointed instrument, such as a pencil 35, to be inserted into the coin-opening 15 through the bottom, thereby lifting the coin D² out of the coin-opening, as indicated in dotted

lines in Fig. 2. This refunding of an insufficient number of coins is one of the more important features of my invention. If an intending purchaser were to lose a coin in this way, he would become prejudiced against the machine and refuse to patronize it.

To adapt a machine for operation by more than two coins—say, three coins—, it is only necessary to increase the thickness of the coin-carrier. Thus, in Fig. 8, I have shown a coin-carrier C' consisting of three sections, c', c² and c³, which are secured together in a manner similar to the sections 11 and 12 of the coin-slide C. The increased depth of the chamber R' for the coin-carrier C' is secured by simply using an additional pair of packing plates or strips 9. The sections of the coin-carrier being uniform, any desired depth of coin-carrier is readily secured by simply adding on or taking away the required number of these sections. The packing plates 9 being all uniform, the desired depth of the chamber or recess which accommodates the coin-carrier is secured by simply adding or taking away, as the case may be, the required number of packing plates. It is preferable that the sections of the coin-carrier have each a thickness equal to the thickness of a proper coin. In this way, a machine intended to be operated only by two coins, will have a coin-carrier consisting of two sections; a machine to be operated only with three coins, will have a coin-carrier consisting of three sections; and so on.

Another advantage of my invention is that the coin-carrier may be changed without disturbing the position of the ejector E. This obviates the necessity of adjusting either the ejector or the position of the magazine M. The adjustment of the machine to operate with the desired number of coins may readily be accomplished by the agent in charge of the machine, without the necessity of sending the entire machine back to the shop. All that the agent requires is a supply of packing plates 9 and coin-carrier sections. By simply inserting the required number of packing plates and the required number of sections for the coin-carrier, the machine may be changed to operate with a predetermined plurality of coins. The machine can easily be restored to its previous condition by simply removing the required number of packing plates and the required number of sections from the coin-carrier.

As previously stated, the specific mechanism herein illustrated and described is merely for the purpose of explaining my invention and is not intended as a limitation. The basic features of my invention may be embodied in other forms than that herein set forth without departing from

the invention as defined in the appended claims.

Having thus described my invention, what I claim as new and desire to secure by Letters Patent of the United States, is:

- 5 1. In a coin-controlled vending machine, a hand-operable coin-carrier having an opening to receive a prescribed plurality of coins face to face, and carry them into operative position, an ejector for the goods, and a member controlled by the combined thickness of the coins on said carrier for permitting operation of said ejector, said member remaining inoperative when an insufficient number of coins is deposited, said coin-carrier being adapted to return an insufficient number of coins to a refunding position.
- 10 2. In a coin-controlled vending machine, a hand-operable coin-carrier adapted to receive a prescribed plurality of coins and carry them into operative position, and an ejecting member controlled by the combined action of all of said coins, said member remaining inoperative when an insufficient number of coins is deposited, said coin-carrier being adapted to return an insufficient number of coins to a refunding position.
- 15 3. In a coin-controlled vending machine, a casing provided with a coin-entrance slot, a hand-operable coin-carrier having an opening normally in alignment with said slot to receive a prescribed plurality of coins face to face, the combined thickness of said coins being substantially equal to the depth of said coin-opening, a member controlled by the combined thickness of the coins on said carrier, said member remaining inoperative when an insufficient number of coins is deposited, said coin-carrier being adapted to return an insufficient number of coins to said coin-entrance slot for removal, and a goods-ejector controlled by said member.
- 20 4. In a coin-controlled vending machine, a casing provided with a coin-entrance slot, a horizontally reciprocable coin-slide having an opening normally in alignment with said slot to receive a prescribed plurality of coins superposed face to face, the combined thickness of said coins being substantially equal to the depth of said coin-opening, a member controlled by the combined thickness of the coins on said slide, said member remaining inoperative when an insufficient number of coins is deposited, said slide being adapted to return an insufficient number of coins to said coin-entrance slot for removal, and a goods-ejector controlled by said member.
- 25 5. In a coin-controlled mechanism, a hand-operable coin-carrier consisting of a plurality of separable sections arranged face to face, said coin-carrier being provided

with an opening for receiving a predetermined plurality of deposited coins face to face, the combined thickness of said coins being substantially equal to the thickness of said coin-carrier, the number of said separable sections being readily varied to vary the number of coins required for operating the mechanism, and a member controlled by the combined thickness of the coins on said carrier, said member remaining inoperative when an insufficient number of coins is deposited, said coin-carrier being adapted to return an insufficient number of coins to a refunding position.

6. In a coin-controlled mechanism, a casing having a coin-entrance slot, a reciprocable coin-slide consisting of a plurality of plate sections arranged face to face and separably connected together, said slide being provided with an opening normally in alignment with said slot for receiving a predetermined plurality of deposited coins face to face, the combined thickness of said coins being substantially equal to the thickness of said slide, the number of said separable sections being readily varied to vary the number of coins required for operating the mechanism, and a member controlled by the combined thickness of the coins on said slide, said member remaining inoperative when an insufficient number of coins is deposited, said coin-slide being adapted to return an insufficient number of coins to said coin-entrance slot for removal.

7. In a coin-controlled vending mechanism, a top plate provided with a coin-entrance slot, a bottom plate secured to said top plate, packing means arranged between said plates to space the latter the required distance, said plates and said packing means forming a chamber, the thickness of said packing means being readily varied to vary the depth of said chamber, a hand-operable coin-slide movable in said chamber and consisting of a plurality of separable sections superposed face to face, the combined thickness of said sections being substantially equal to the depth of said chamber, said coin-slide being provided with an opening normally in alignment with said coin-entrance slot to receive a predetermined plurality of coins, the number of said separable sections being readily varied to vary the number of coins required for operating the mechanism, and a member controlled by the combined thickness of the deposited coins, said member remaining inoperative when an insufficient number of coins is deposited, said coin-slide carrying an insufficient number of coins back to said coin-entrance slot for removal.

8. In a coin-controlled mechanism, a casing, means arranged to form a chamber within said casing, said means being readily

- adjustable to vary the depth of said chamber, a coin-carrier movable in said chamber and consisting of a plurality of separable sections connected together face to face, the combined thickness of said sections being substantially equal to the depth of said chamber and the number of said sections being readily variable in accordance with the depth of said chamber, said coin-carrier having an opening to receive a predetermined number of coins face to face so that the combined thickness of the deposited coins is substantially equal to the combined thickness of said sections, means for manually operating said coin-carrier, means for normally locking said coin-carrier against operative movement, and a member actuated by said coin-carrier and controlled by the combined thickness of a predetermined number of coins on the carrier to unlock said locking means and permit full movement of the carrier, said locking means remaining in locking position when an insufficient thickness of coins is on said carrier.
9. In a coin-controlled mechanism, a casing having a coin-entrance slot, means arranged to form a chamber within said casing, said means being readily adjustable to vary the depth of said chamber, a hand-operable coin-carrier movable in said chamber, said coin-carrier consisting of a plurality of separable sections connected together face to face, the combined thickness of said sections being substantially equal to the depth of said chamber and the number of said sections being readily varied in accordance with the depth of said chamber, said coin-carrier having an opening normally in alignment with said coin-entrance slot to receive a predetermined number of coins face to face, so that the combined thickness of the deposited coins is substantially equal to the combined thickness of said sections, and a member controlled by the combined thickness of the coins on said carrier, said member remaining inoperative when an insufficient number of coins is on said carrier, said carrier being adapted to return an insufficient number of coins to said coin-entrance slot.
10. In a coin-controlled vending machine, a casing provided with a coin-entrance slot and with a vertical magazine for the goods, a hand-operable ejector movably mounted within said casing, a coin-slide connected with said ejector and having an opening normally in alignment with said slot to receive a predetermined plurality of coins face to face, the thickness of said coin-slide being readily adjustable to vary the number of required coins without disturbing the position of said ejector, and a member controlled by the combined thickness of the deposited coins to permit said ejector to eject the goods from said magazine, said ejector remaining inoperative when an insufficient number of coins is in said slide, said slide being adapted to carry an insufficient number of coins back to said coin-entrance slot for removal.
11. In a coin-controlled mechanism, a casing provided with a shallow chamber, means for varying the depth of said chamber, a coin-carrier movable in said chamber in the plane thereof and having an opening to receive a predetermined plurality of coins face to face, said coin-carrier being substantially of the same width as said chamber, means for varying the thickness of said coin carrier to correspond to the depth of said chamber, means for manually operating said coin-carrier, means for normally locking said coin-carrier against operative movement, and a member actuated by said coin-carrier and controlled by the combined thickness of a predetermined number of coins on the carrier to unlock said locking means and permit full movement of the carrier, said locking means remaining in locking position when an insufficient thickness of coins is on said carrier.
12. In a coin-controlled mechanism, a casing provided with a shallow chamber, means for varying the depth of said chamber, a coin-carrier movable in said chamber in the plane thereof and having an opening to receive a predetermined plurality of coins face to face, said coin-carrier being substantially of the same width as said chamber, means for varying the thickness of said coin-carrier to correspond to the depth of said chamber, and a member acted upon only by the combined thickness of the predetermined number of coins, said coin-carrier being adapted to return an insufficient number of coins to a refunding position.
13. In a coin-controlled mechanism, a coin-carrier having an opening to receive a predetermined plurality of coins face to face, and a member controlled by the combined thickness of said predetermined number of coins, said member remaining inoperative when an insufficient number of coins is in said coin-carrier, said coin-carrier being adapted to return an insufficient number of coins to a refunding position.
14. In a coin-controlled mechanism, a casing provided with a coin-entrance slot, a coin-carrier having an opening normally in alignment with said slot to receive a predetermined plurality of coins face to face, and a member controlled by the combined thickness of said predetermined number of coins, said member remaining inoperative when an insufficient number of coins is in said coin-carrier, said coin-carrier being adapted to return an insufficient number of coins to said coin-entrance slot for removal.
15. In a coin-controlled mechanism, a coin-carrier consisting of a plurality of sec-

6
tions separably connected together face to face to form a member of predetermined thickness, said coin-carrier having an opening to receive a plurality of coins face to face, so that the combined thickness of said coins is substantially equal to the combined thickness of said sections, the number of said sections being readily varied to vary the thickness of the coin-carrier in accordance with the combined thickness of the predetermined number of required coins, means for manually operating said coin-carrier, means for normally locking said coin-carrier against operative movement, and a member actuated by said coin-carrier and controlled by the combined thickness of a predetermined number of coins on the carrier to unlock said locking means and permit full movement of the carrier, said locking means remaining in locking position when an insufficient thickness of coins is on said carrier.

16. In a coin-controlled mechanism, a coin-carrier consisting of a plurality of sections separably connected together face to face to form a member of predetermined thickness, said coin-carrier having an opening to receive a plurality of coins face to face, so that the combined thickness of said coins is substantially equal to the combined thickness of said sections, the number of said sections being readily varied to vary the thickness of the coin-carrier in accordance with the combined thickness of the predetermined number of required coins, and a member controlled by the combined thickness of the required coins, said member remaining inoperative when an insufficient number of coins is in said coin-carrier, said coin-carrier being adapted to return an insufficient number of coins to a refunding position.

17. In a coin-controlled mechanism, a normally locked coin-carrier adapted to receive a predetermined plurality of coins face to face, and means controlled by the combined thickness of said coins to unlock said coin-carrier for operative movement, said means remaining in locking position when an insufficient number of coins is in said coin-carrier.

18. In a coin-controlled mechanism, a normally locked coin-carrier adapted to receive a predetermined plurality of coins face to face, and means controlled by the combined thickness of said coins to unlock said coin-carrier for operative movement, said means remaining in locking position when an insufficient number of coins is in said coin-carrier, said coin-carrier being adapted to return an insufficient number of coins to a refunding position.

19. In a coin-controlled mechanism, a casting provided with a coin-entrance slot, a normally locked coin-carrier having an opening normally in alignment with said

slot to receive a predetermined plurality of coins face to face, a device controlled by the combined thickness of said coins to unlock said coin-carrier for operative movement, said device remaining in locking position when an insufficient number of coins is in said coin-carrier, said coin-carrier being adapted to return an insufficient number of coins to said coin-entrance slot for removal.

20. In a coin-controlled mechanism, a normally locked coin-carrier having an opening to receive a predetermined plurality of coins face to face, the combined thickness of said coins being substantially equal to the thickness of said coin-carrier, said coin-carrier consisting of a plurality of sections removably connected together face to face, the number of said sections being readily varied to vary the number of coins required to equal the combined thickness of the sections, and means controlled by the combined thickness of the coins in the coin-carrier to unlock said coin-carrier for operative movement, said means remaining in locking position when an insufficient number of coins is in said coin-carrier.

21. In a coin-controlled mechanism, a coin-carrier having an opening to receive a predetermined plurality of coins face to face, the combined thickness of said coins being substantially equal to the thickness of said coin-carrier, said coin-carrier consisting of a plurality of sections removably connected together face to face, the number of said sections being readily varied to vary the number of coins required to equal the combined thickness of the sections, means for manually operating said coin-carrier, means for normally locking said coin-carrier against operative movement, and a member actuated by said coin-carrier and controlled by the combined thickness of a predetermined number of coins on the carrier to unlock said locking means and permit full movement of the carrier, said locking means remaining in locking position when an insufficient thickness of coins is on said carrier.

22. In a coin-controlled mechanism, a horizontally reciprocable coin-slide adapted to receive a predetermined plurality of coins face to face, means for normally locking said coin-slide against operative movement, and a device controlled by the combined thickness of said predetermined plurality of coins to unlock said means and allow operative movement of the coin-carrier, said device remaining in locking position when an insufficient number of coins is in said coin-carrier, said coin-carrier being adapted to carry an insufficient number of coins into a refunding position.

23. In a coin-controlled mechanism, a coin-carrier consisting of a plurality of parallel flat sections arranged face to face and

- movable as a unit, each section having an opening to receive a coin, and means actuated only when coins are simultaneously present in all of said openings, said means remaining unactuated when less than the full number of coins is in said coin-carrier, said coin-carrier being adapted to return an insufficient number of coins to a refunding position.
24. In a coin-controlled mechanism, a horizontally movable coin-slide consisting of a plurality of superposed plates removably connected together, each plate having an opening to receive a coin, and means actuated only when a coin is present in each of said openings, said coin-slide being adapted to carry an insufficient number of deposited coins into a refunding position.
25. In a coin-controlled vending mechanism, a coin-carrier consisting of a plurality of sections connected together to move as a unit, each section having an opening to receive a coin, and an ejecting member actuated into operative position only when coins are simultaneously present in all of said openings, said coin-carrier being adapted to return an insufficient number of coins to a refunding position without causing actuation of said ejecting member.

In witness whereof, I hereunto subscribe my name this 24th day of September, 1918.

ALBERT D. GROVER.
